Attorney

UNITED STATES PATENT OFFICE

GEORGE A. CARNEY, OF DORCHESTER, MASSACHUSETTS

SKATE

Application filed March 25, 1930. Serial No. 438,850.

This invention relates to skates, to the manner of securing the blade to the frame of the skate, and to the runners and blade, herein-after termed as a unit "a four runner blade", being interchangeable and comprising eight skating surfaces in one unit.

The objects of the invention are to provide a skate which can be prepared for a full season's use with one grinding; to furnish a 10 skate construction providing for a change of the skating edge which has become dull in use for a sharper edge, at any convenient time and place, on the ice or elsewhere, without the necessity of expensive tools or equipment; to 15 render available for ready change and use, four distinct interchangeable blades with eight separate and distinct skating edges, two of the edges being on each blade; to provide increased strength and rigidity to 20 skate blades; to provide a blade of the kind described adaptable for interchangeable end to end use; to provide an interchangeable skate blade affording means for locking nuts in 25 fixed position as a part of the particular means by which the blade is secured to the 30 frame of the skate; to reduce the number of machined parts required for an interchangeable blade construction; to eliminate all 35 threading and tapping in the manufacturing process; to utilize open market commodities in the assembled product; to eliminate the use of expensive tools and equipment in the manufacturing process; to reduce production overhead costs; and to provide the various other advantages and results made evident from the following specification.

Briefly and concisely stated, I accomplish the objects of my invention by providing an integral four runner blade construction 40 adaptable for end to end use, two of the runners being positioned opposite each other and at right angles to the others, so that each runner is at an angle of ninety degrees from the adjoining runner and by providing a 45 series of transverse openings in each of the four runners, any one of said series adaptable to register with other and similar transverse openings in the longitudinal blade holding portions of the frame of the skate so that 50 transversely disposed holding bolts may be

readily passed through said transverse openings in any one of the runners when registered with the transverse openings in said longitudinal portions, one of the runners disposed at ninety degrees to the blade in use, affording 55 locking means for holding in fixed position square nuts placed on the threaded end of said transversely disposed bolts.

Referring to the accompanying drawings which form a part of this specification, and in which similar letters of reference refer to similar parts throughout the various views, Figure 1 shows the sole of a skating shoe with my multiple blade skate secured thereto. Figure 2 shows a cross sectional view thereof 60 on the line 2-2 in Figure 1. Figure 3 shows an enlarged detail of the heel portion of the skate frame. Figure 4 shows the detail of the bolt and the nut employed at the threaded end thereof as means for holding the blade 65 in the frame of the skate. Figure 5 shows a side view of the skate shown in Figure 1.

Referring again to the figures, A¹ shows the forward end of the sole of a skating shoe. A² shows the heel end thereof. B¹ shows the 75 skate frame designed for attachment to the forward end of the sole of the skating shoe. B² shows that portion of the skate frame designed for attachment to the heel end of the sole of said shoe. C¹ and C² show blade 80 holding clamping members at the heel end of the skate frame. D¹ and D² shows the blade holding clamping members of the skate frame positioned at its forward end. E¹, E², E³, and E⁴ show the respective runners each positioned at 85 right angles to the adjoining runner. F shows the transverse openings in the blade holding clamping members of the skate frame positioned to register with the openings F² in the blade. H shows the holding bolts. H² shows 90 the thread on said bolts. I shows the nuts adaptable to fit the thread H² on the bolts H. Tightening is effected by turning the bolt, the nut itself being locked against a runner as shown in Figure 2.

While I have illustrated and described a preferred construction for carrying my invention into effect, this is capable of variation or modification without departing from the spirit of the invention. I therefore do not 100

wish to be limited to the exact details of construction herein set forth but desire to avail myself of such variations and modifications as come within the scope of the appended claims.

- 5 6. Having thus described my invention, I claim as new and desire to secure by Letters Patent of the United States of America:—
1. A skate comprising a four runner blade, each runner angularly disposed to the others and having transverse openings therein, a frame comprising sole and heel plate brackets formed with pressed out portions having transverse openings therein arranged to register with the transverse openings in any one of said runners, and clamping elements extending through said transverse openings.
  - 10 2. In combination with a shoe, a skate secured thereto, consisting of a four runner blade, each runner angularly disposed to the others, a heel plate and a toe plate each forming two clamping portions, one of said runners housed between the clamping portions of said toe and heel plate, transversely disposed holding bolts extending through said runner and clamping portions, and square nuts on the ends thereof, flat side of said nuts held in fixed position by the surface of one of the runners.
  - 15 3. A skate consisting of a four runner blade each runner angularly disposed to the others, a heel plate and a toe plate, each forming two clamping portions, one of said runners housed between the clamping portions of said toe and heel plate, transversely disposed holding bolts extending through said runner and clamping portions, and square nuts on the ends thereof, a flat side of said nuts held in fixed position by the surface of one of the runners.
  - 20 4. A skate having a frame and a four runner blade, each runner angularly disposed to the others, transversely disposed holding bolts extending through said frame and one of said runners, nuts on the ends of said bolts, any one of said runners adaptable to be removably secured by said bolts to said frame, the runner oppositely disposed to the one secured to the frame adaptable for use in skating, a third runner adaptable to act as means to hold said nuts in fixed position, and the fourth runner adaptable for interchangeable use with any one of the other runners.

In testimony whereof I affix my signature.
GEORGE A. CARNEY.
